CHECK CONTROLLED MECHANISM

Harry B. Stoner and Rodney W. Phillips,
Aurora, Ill.

Application January 26, 1938, Serial No. 186,916

4 Claims. (Cl. 194—102)

This invention relates to that portion of a check controlled mechanism, commonly referred to as a "coin slide" or "coin chute," which is acted upon by a check to unlock the mechanism for an operating cycle. Specifically, the invention relates to the disposal of the check after it has been utilized in unlocking the mechanism or initiating a cycle of operation thereof, and has as its primary object to provide, in a mechanism capable of utilizing checks of different sizes, check discharging means that is optionally adjustable so as to, under one adjustment, separate the larger from the smaller checks and deliver them to different discharge stations, and, under another adjustment, deliver all of the checks to a single station.

Many check controlled machines are adapted to utilize either or both of several sizes of checks such as, for example, five cent coins and slugs of slightly smaller diameter. In some cases, it will be desirable to separate the slugs from the coins and deliver them to different receptacles, while in other cases it may be preferable to deliver both to the same receptacle. The present invention makes it possible to change the adaptation of the machine from one to the other of these conditions by a very simple adjustment that may be performed in an instant.

Another object of the invention is to provide a selector device, applicable to the horizontal "coin slide" type of check mechanism, for separating the checks by carrying the larger checks away from the initial discharge station where all of the checks are received by the selector, the smaller checks being allowed to pass directly through the selector at the initial discharge station.

Another object is to provide a simple arrangement for driving the selector in timed relationship with the movement of the operating plunger of the "coin slide."

A further object of the invention is to provide a novel check exhibitor, adapted to display a maximum number of played checks in a minimum amount of space, particularly in connection with a horizontal slide type of check mechanism. The invention, in addition, aims to provide a simplified arrangement of slide, exhibitor, and selective discharge mechanism, in which the exhibitor and selector are closely correlated, utilizing a common drive mechanism, and the exhibitor serving as the means for delivering the checks to the selector.

With the foregoing and other objects in view which will appear as the description proceeds,

the invention consists in certain novel features of construction, arrangement and combination of parts hereinafter more fully described, illustrated in the accompanying drawings, and particularly pointed out in the appended claims, it being understood that various changes in the form, proportion, size and minor details of the structure may be made without departing from the spirit or sacrificing any of the advantages of the invention.

For the purpose of facilitating an understanding of my invention, I have illustrated in the accompanying drawings a preferred embodiment thereof, from an inspection of which, when considered in connection with the following description, my invention, its mode of construction, assembly and operation, and many of its advantages should be readily understood and appreciated.

Referring to the drawings in which the same characters of reference are employed to indicate corresponding or similar parts throughout the several figures of the drawings:

Fig. 1 is a plan view of a check mechanism embodying the invention, with the plunger in retracted position;

Fig. 2 is a similar view with the plunger in advanced position, parts being broken away to better illustrate the construction;

Fig. 3 is an inverted plan view of a portion of the mechanism, illustrating particularly the selector unit in advanced position, opened up to discharge the larger checks at the second discharge station;

Fig. 4 is a similar view of the selector in retracted and closed position;

Fig. 5 is a similar view of the selector, adjusted to constantly open position so as to discharge all checks at the initial discharge station;

Fig. 6 is a side elevational view of the mechanism;

Fig. 7 is a sectional view taken longitudinally through the selector unit as indicated by the line 7—7 of Fig. 5;

Fig. 8 is a sectional view taken on the line 8—8 of Fig. 1; and

Fig. 9 is a sectional view taken on the line 9—9 of Fig. 1.

The preferred form of the invention illustrated in the drawings is embodied in a well known slide mechanism comprising a slideway 10 formed with a collar flange 11 for attachment to a vertical wall of the machine which the mechanism controls. An operating plunger 12 is slidably mounted in the slideway 10. At its outer end 55

the plunger 12 is provided with the usual handle 13 by means of which it may be advanced and retracted in the slideway 10. In its intermediate region, the plunger 12 is provided with a check 5 receiving opening 14 adapted, when the plunger 12 is in retracted position as shown in Fig. 1, to register with the forward end of a guide slot 15 in the skirt 16 of the guideway 18 and with a small coin eliminating opening 17 in the bottom 10 wall of the skirt 16, whereby coins and slugs of the proper size range may be readily deposited in the opening 14 and rest upon the shoulder formed by the said bottom wall between the openings 14 and 17.

15 A check thus deposited will be carried by the plunger 12, when the latter is pushed inwardly, to a position directly below a sight opening 18 in a grille member 19 attached at 20 to the upper side of the forward region of the slideway 12. In this 20 position the plunger 12 will be fully advanced as shown in Fig. 2. During this operating stroke of the plunger 12, the check may be utilized to unlock the mechanism by moving aside certain locking elements that would otherwise obstruct the 25 movement of the plunger. Not forming part of the present invention, such locking mechanism is not shown. The movement of the plunger may be employed in a well known manner to transmit operating movement to certain parts of the machine to which the invention is applied.

In the slideway 18 directly below the sight opening 18 is an opening 21 as shown in Fig. 8, through which the check will drop after being released from the plunger. The check will alight 30 upon a gate 22 mounted for sliding movement in channels 23 formed in the slideway 10, along a path parallel to and below that of the plunger 12 as shown in Fig. 9. The gate 22 is adapted to reciprocate in timed relation to the movement of the plunger 12, being controlled by the latter through a driving connection including a pin 24 fixed in its forward end and projecting upwardly through a slot 25 in the plunger. As the plunger advances, the rear end of the slot 25 will engage 35 the pin 24 as shown in Fig. 2, and during the remainder of the advancing stroke, the gate 22 will be carried along with the plunger, moving from the position shown in Fig. 8 to a position wherein the rear region of the gate, designated 26, will lie below the opening 21 so as to support the check while the plunger is in advanced position.

As the plunger is retracted, the forward end of the slot 25 will contact the pin 24, and during the remainder of the retracting movement, the gate 55 22 will be returned to the position shown in Fig. 8, in which position an opening 27 in the gate will register with the opening 21, allowing the check to drop into the exhibitor which will now be described.

60 Flanges 28 are formed on the lower side of the slideway 10 below the gate 22. To the flanges 28 is secured by means of screws 29, a roughly circular exhibitor casing 30 including upper and lower walls 31 and 32 respectively, secured together in spaced relationship by rivets 33 and washers 34 through which the rivets extend. Between the walls 31 and 32 is a conveyor disc 35, which is journaled for rotation upon a stud 36 mounted in the walls 31 and 32. Washers 37 65 space the upper and lower faces of the disc from the walls 31 and 32. The conveyor disc 35 is provided with a circularly arranged series of check receiving openings 38, spaced equidistantly from each other and from the stud 36. In 70 the upper casing wall 31 is an annular slot or

series of slots 39, registering with the series of openings 38, so that the checks in most of the openings 38 are exposed to view from above. The exhibitor casing 30 is attached to the slideway 10 so that the latter is substantially tangent to 5 one side of the casing, and so that a minimum area of the casing is covered by the slideway. The reasons for this arrangement will more fully appear hereinafter.

In the edge of the disc 35 is formed a series of 10 notches 40, one for each of the openings 38. Pivoted on the stud 36, below the casing 30, is an arm 41, to the outer end of which is pivoted a pawl 42 as shown in Fig. 2, arranged to engage with the notches 40 for advancing the conveyor 15 disc in step by step movements. The pawl 42 is pivoted on a pin 43 mounted at its ends in a yoke 44 forming one end of a driving link 45 by means of which the arm 41 is connected to the plunger 12 to receive movement therefrom. The 20 pawl 42 is centered in the yoke 44 by spacing washers 46. The pin 43 extends through the pawl 42, the washers 46, and the end of the arm 41. The pawl 42 has a tail portion 47 which is attached to one end of a coil spring 48, serving to 25 resiliently urge the pawl into engagement with the disc 35.

Secured to the plunger 12 near its forward end, and projecting laterally, is a bracket 49 having a slot 50, parallel to the longitudinal axis of the 30 plunger. A pin 51 mounted in the end of the link 45 opposite the yoke 44, extends through the slot 51 and is secured therein by a cotter pin 52 and a washer 53.

As the plunger 12 is advanced, the rear end 35 of the slot 50 will engage the pin 51 and during the remainder of the advancing stroke, the arm 41 will be oscillated to retract the pawl 42 to the position shown in Fig. 2. As the plunger is retracted, the pawl 42 will engage in a notch 40 and 40 rotate the disc 35 one step. At the completion of this step, a holding pawl 54, pivoted at 55 between the casing walls 31 and 32, will move into engagement with one of the notches 40 under the pull of a spring 56 attached at one end to an ear 45 57 formed on the pawl 54 and at its other end to an ear 58 struck downwardly from the lower wall 32.

The exhibitor is arranged so that when the disc 35 is in a position defined by engagement of 50 the pawl 54 with a notch 40, one of the openings 38 will register with the opening 21 in the slide-way so that the check, when released by the gate 22, will drop into said opening 38 through an opening 85 in the wall 41. In this position, it 55 will still be visible through the sight opening 18, being exposed through an opening 59 forming an enlargement of the slot 25. During the advancing step described in the preceding paragraph, this check will be advanced to the position designated 60 in Fig. 1. The check, shown in Fig. 1 at 61, will then be visible through the beginning 65 end of the annular sight opening 39. Thus the played checks are all visible until finally discharged from the exhibitor, the discharge position being indicated at 62 in Fig. 1. This is the only position that is not exposed to view. Thus a maximum of exhibition is achieved in a minimum of space, the checks passing entirely around a circular path before being discharged at 62. The 70 above mentioned arrangement of the exhibitor casing 30 with relation to the slideway 10 makes this possible, as well as providing for the driving connection between the plunger 12 and the arm 75

41, such driving connection extending around the periphery of the casing 30.

The selective discharge mechanism includes the arm 41, near the outer end of which is formed a jaw 63 as shown in Fig. 3 and Fig. 7. A coacting jaw 64 is formed at the end of an arm 65 which is pivoted on the stud just above the arm 41. The jaws 64 and 63 together form a basket-like structure, each including a downwardly extending shoulder portion 66, a bottom member 67, an upwardly extending end wall 68, and an upwardly extending side wall 69. The bottom members 67 have semi-circular notches 70 together forming a circular opening when the jaws are in normal closed relation as shown in Fig. 4. This opening is of sufficient diameter to pass the smaller checks that are adapted to be employed by the mechanism, but will not pass the larger checks until the jaws are spread as in Fig. 3 and Fig. 5. The jaw 20 64 is normally maintained in closed relationship to the jaw 63 by the pull of the spring 48, one end of which is attached as before stated to the pawl 42 and the other end of which is attached to an ear 71 formed on the arm 65.

25 When the plunger 12 is in retracted position, the selector will be positioned under a discharge opening 72 in the lower wall 32 of the exhibitor casing, at the position 62, which will be herein-after referred to as the initial discharge station.

30 This position of the selector is shown in Fig. 4. As the plunger is advanced, the selector, simultaneously with the retraction of the pawl 42, will be advanced to the second discharge position, designated 73 in Fig. 3, where the jaws 63 and 64 will be spread by the engagement of a tail portion 74 on the arm 65 with the ear 58, causing the arm 65 to stop while the arm 41 continues to advance. When the plunger is retracted, the selector will be moved back to the initial discharge station, and simultaneously the conveyor disc 35 will be advanced, carrying a check to the discharge opening 72 and causing it to drop through said opening into the selector. If a small check, it will pass directly through the selector and be discharged into a small check receptacle. If a large check, it will be retained by the selector until the latter has moved to the second discharge station 73, whereupon it will be released by the spreading of the jaws 63 and 64 to drop 45 into a large check receptacle.

50 If it is desired to collect all of the checks in one receptacle, the selector is adjusted by simply blocking the jaws 63 and 64 apart so that all checks will pass directly through the selector at station 62. This is accomplished by a block member 75, pivoted at 76 on an arm 77 which in turn is pivoted on the stud 36 just below the arm 41. A spring 78, one end of which is attached to an ear 79 on the tail portion 80 of the block member 75 and the other end of which is attached to an ear 81 on the arm 77, serves to urge the block member 75 into alignment with the arm 41 and yet to allow it to yield laterally to pass one of the shoulder portions 66 of the arms 41, 65. By 55 spreading the jaws 63 and 64 with the fingers and rotating the arm 77, therefore, the block 75 will work its way into a position between the adjacent edges of shoulder members 66 as shown in Fig. 5.

70 The operation of the mechanism will be fully apparent from the preceding description.

It is believed that our invention, its mode of construction and assembly, and many of its advantages should be readily understood from the foregoing without further description, and it

should also be manifest that while a preferred embodiment of the invention has been shown and described for illustrative purposes, the structural details are nevertheless capable of wide variation within the purview of our invention as defined in the appended claims.

What we claim and desire to secure by Letters Patent of the United States is:

1. In a check controlled mechanism, in combination with means adapted to employ checks of varying sizes in initiating operation of the mechanism and to then release the checks, selecting means comprising a movable member provided with a pair of relatively movable jaws adapted to receive the checks thus released, an initial discharge station, said movable jaws being adapted to immediately discharge the smaller of the checks it has received at said initial discharge station and retain the larger checks, a second discharge station, link means connecting said movable member with said check controlled mechanism for movement thereby to said second discharge station, resilient means for maintaining said jaws in closed relation, stop means adjacent said second discharge station cooperating with the movable member during movement thereof to effect a spreading of the jaws thereof by causing a halt of one of said jaws and permitting continued movement of the other, adjustable means consisting of a blocking member, means for permanently and rotatively attaching said adjustable member to said movable member and means for adjusting said adjustable member to a position between said jaws for holding the jaws in an open position to discharge all of the checks at said initial discharge station.

2. In a check controlled mechanism, in combination with means adapted to employ checks of varying sizes in initiating operation of the mechanism and to thereafter release the checks, selecting means comprising an oscillable arm having a pair of relatively movable jaws adapted to receive said checks upon release from said first mentioned means, an initial discharge station, retaining means provided on said movable jaws, said jaws being adapted to receive the checks thus released and immediately discharge the smaller checks it has received at said initial discharge station and retain the larger checks within said retaining means thereof, a second discharge station, driving means connecting said first mentioned means to said oscillable arm to swing same during initiation of the operation of said check controlled mechanism, means normally holding said jaws in closed check retaining association, stop means adjacent said second discharge station adapted to halt movement of one of said jaws permitting the other to move with said oscillable arm to thereby effect a spreading of the said jaws causing the retained checks to be discharged at said second discharge station.

3. In a check controlled mechanism in combination with a slide of the type including a normally locked operating plunger adapted to be released for an operating stroke by various sized checks which it releases at the end of the stroke, means for segregating the smaller from the larger of said checks, including an initial discharge station for the smaller of said checks, and a second discharge station for the larger of said checks, selecting means for carrying said checks comprising an arm adapted to swing between said discharge stations, said arm being provided with relatively movable jaws each having the end

thereof fashioned to the form of half of a basket-like structure, means provided upon said swingable arm normally maintaining said jaws in a closed position to cause said halves to cooperate to form thereby a receptacle, said receptacle having an opening in the bottom thereof through which the smaller of said checks are directly discharged to said initial station when released by said plunger, said receptacle being adapted to 10 retain and carry therewithin the larger checks released from said plunger, a lost motion driving means between said plunger and said selecting means for causing same to swing from said initial discharge station to said secondary discharge 15 station on movement of said plunger, and stop means disposed in the path of one of said jaws to halt same and permit the other jaw to continue moving while said selecting means is swinging to said second discharge station, thereby 20 causing said halves of said basket-like structure to separate, opening said receptacle and thereby permitting said larger checks to be released therefrom at said second discharge station.

4. In a check controlled mechanism, in combination with a slide of the type including a normally locked operating plunger adapted to be released for an operating stroke by a check which it releases at the end of the stroke, means for

depositing said check within a discharge station comprising an arm adapted to swing between the point where said check is released and the said discharge station carrying said check from said point to said station, said arm being provided with relatively movable jaws each having the end thereof fashioned to the form of half of a basket-like structure, means provided on said swingable arm for normally maintaining said jaws in a closed position to cause said halves 10 to cooperate to form thereby a receptacle, said receptacle being adapted to catch, retain and carry therewithin the check released from said plunger at said point, a lost motion driving means between said plunger and said swinging 15 arm for causing same to swing from said release point to said discharge station on movement of said plunger, and stop means disposed in the path of one of said jaws to halt same and permit the other jaw to continue moving with said 20 swinging arm while same is swinging to said discharge station, thereby causing said halves of said basket-like structure to separate, opening said receptacle and thereby permitting said check to be released therefrom at said discharge 25 station.

HARRY B. STONER.
RODNEY W. PHILLIPS.
